UNITED STATES PATENT OFFICE.

ROBERT G. SAVILL, OF PHILADELPHIA, PENNSYLVANIA, ASSIGNOR TO THOMAS M. SAVILL, ROBERT G. SAVILL, AND WILLIAM S. SAVILL, ALL OF PHILADELPHIA, PENNSYLVANIA, COPARTNERS TRADING AS THOMAS SAVILL'S SONS.

DESIGN FOR A FAUCET.

46,238.

Specification for Design.

Patented Aug. 4, 1914.

Application filed May 20, 1914. Serial No. 839,912. Term of patent 14 years.

To all whom it may concern:

Be it known that I, ROBERT G. SAVILL, a citizen of the United States, and a resident of Philadelphia, county of Philadelphia, Pennsylvania, have invented a new, original, and ornamental Design for Faucets, which is shown in the accompanying drawings, in which—

Figure 1 is a side elevation of a faucet

embodying the design, and Fig. 2 is a plan view.

I claim:

The ornamental design for a faucet substantially as shown.

ROBERT G. SAVILL.

Witnesses:

HARRY S. LIGGETT,
WILLIAM J. LODGE.
